UNITED STATES PATENT OFFICE.

MYRON T. HAYER, OF WORCESTER, MASSACHUSETTS.

PUSH-BUTTON DOORKNOB.

Application filed September 1, 1921. Serial No. 497,486.

To all whom it may concern:

Be it known that I, MYRON T. HAYER, a citizen of the United States, residing at Worcester, in the county of Worcester and State of Massachusetts, have invented a new and useful Push-Button Doorknob, of which the following is a specification.

This invention relates to a door knob and latch of the type in which the latch is operated by a push button in the center of the knob instead of by the rotation of the knob.

The principal objects of the invention are to improve the construction of such knobs by providing simplified connections from the push buttons to the inside levers for operating the latch; by providing an arrangement for assembling the parts by which there will be no necessity of using any screws from the outside of the device at all and which will eliminate all screw heads or bolts on the exterior surfaces; by providing a convenient construction by which the device cannot be dismounted from either side alone but must be reached from both sides in order to get it apart; by providing simple means by which only one spring is required and that one on the latch itself; and by providing improved lever constructions for operating the latch in opposition to the spring.

Further objects and advantages of the invention will appear hereinafter.

Reference is to be had to the accompanying drawings, in which—

Fig. 1 is a side view of a preferred embodiment of this invention showing the latch casing in elevation;

Fig. 2 is a transverse sectional view on the line 2—2 of Fig. 1, and

Fig. 3 is a longitudinal central sectional view on the line 3—3 of Fig. 1.

I have shown the device as comprising a latch casing 10 set into the door 11 and provided with a fixed plate 12 on the end which can be set into a mortise on the edge of the door. As will appear later, this need not be fixed by screws or bolts.

In the casing 10 there is the usual latch 13 having a rod 14 extending back in the casing and provided with a head 15 on the inner end slidable in the casing. On the bolt 14 is a spring 16 pressing against the rear of the latch at one end and against a stationary wall of the casing 10 at the other so as normally to hold the latch out in the position shown, for latching the door.

I have shown the casing 10 as fixed with respect to two opposite inner casings 17 by screws 18 but these parts can be made if desired, so as to be connected positively without screws. In this inner casing 17 are located a pair of levers 20, each having a convex head 21 and a projecting operating end 22 extending substantially at right angles to each other. A feature in mounting the casing 17 on the casing 10 is to make the relation between the operating levers 20 and the head 15 constant regardless of the thickness of the door. Through a guide 23 integral with each casing 17 projects a plunger 24 which has an oblong cross-section throughout most of its length but has a circular cross-section at its outer end that is screw threaded for a button 25. The oblong cross-section of plunger 24 acts as a limit-stop for its outward motion and also prevents rotation through the guide 23 when the button 25 is screwed on.

By pushing in the push button the plunger 24 engages the end 21 of the lever 20 and forces the end 22 of the lever back against the front of the head 15. This draws back the bolt 14 against the action of the spring 16. These parts are duplicated on the other side of the door.

Engaging the door on each side is a metal casing 26 which is hollow and of a general conical shape preferably. This houses the plunger 24 and supports the stationary knob 27, and is so shaped that the guide piece 23 keeps it firm if the knob is given a twist. This knob has a plug 28 in its center which has a passage receiving the cylindrical part of the plunger 24 and its head closes the cylindrical recess in which the push button 25 operates.

This plug 28 is provided with two parallel passages through it, one of them screw threaded and the other having a countersunk outer end. In these two passages are located the ends of two bolts 30. These bolts are placed oppositely, the head of one bolt being located in the countersunk passage and the opposite end of the other bolt screwing into the threaded passage. These passages on the other side of the door are arranged in the opposite manner.

When the device is set up, one of the bolts 30 is put in in one direction and screwed in so as to hold both knobs in position and the other bolt is inserted in the

other direction from the other side of the door. When both are secured in this way it will be seen that it is impossible to dislodge or loosen the parts from one side only. 5 One bolt can be taken out from one side but the other cannot be and it will be sufficient to hold the parts together for ordinary purposes. The push buttons 25, screwing as they do on the plungers 24, can be 10 detached very readily and removed with equal readiness but that does not expose the door knob in such a way as to permit the whole thing being removed from one side.

It is to be observed that the whole thing, 15 including the latch, is held in place by the two bolts 30, both of these being internal and entirely unexposed. Therefore, there is no need of placing any screws through the flat flanges at the bottom of the casing 26 20 or even through the plate 12. Although screws may be used in the latter, if desired, all other external screws are eliminated. The passages in the casings 17 through 25 which the bolts 30 are inserted are made conical so as to guide these bolts in readily and shorten the time required for attachment.

It will be seen also that the plunger 24 is guided accurately and centered so that, no 30 matter where the levers 20 may be located, the plunger is always in the right position and it cannot bind at the end but is self-centering. It will be seen that each push button will work to withdraw the latch independently of the other or of its condition. 35 The device involves few parts and is capable of being constructed by ordinary operations involving comparatively small expense. In addition to this the device possesses all 40 the advantages of the usual push button door knob.

Although I have illustrated and described only a single form of the invention, I am aware of the fact that modifications can 45 be made in the details of construction without departing from the scope of the invention as expressed in the claims.

Therefore, I do not wish to be limited to all the details of construction herein 50 shown and described, but what I do claim is:—

1. In a push button door knob, the combination of a pair of knobs located opposite each other, a pair of bolts connecting said 55 knobs and extending through the door, each bolt having a head at one end and a thread at the other, said bolts extending through the door in opposite directions, each bolt being connected with one knob by its head 60 and with the other knob at its opposite screw threaded end, whereby the knobs cannot be released from each other from one side of the door alone.

2. In a push button door knob, the combination of a pair of stationary knobs lo-

cated opposite each other and in alignment, a pair of bolts connecting said knobs and extending through the door, one bolt extending in one direction and the other in the other direction, one bolt connected with 70 each knob by its head and the other bolt at its opposite end which is screw-threaded, each knob having a recess in its outer side and a guide opening between the bolts, a plunger in said guide opening, a latch, 75 means by which either plunger can operate the latch, each plunger having a screw threaded outer end, and a push button detachably screwed on each screw threaded end and closing the outer face of the knob. 80

3. In a push button door knob, the combination with a pair of knobs, a push button on each knob, and a plunger adapted to be operated by each button, of a casing having an opening for a plunger and provided with an opening therethrough having walls inside gradually sloping toward each other for self-centering purposes, and a bolt passing through said opening and securing the two knobs directly to each other. 90

4. In a push button door knob, the combination with a door having a single passage therethrough, of a pair of hollow casings for engaging the opposite sides of the door to cover said passage, knobs on the opposite sides of said casings, said knobs each having a passage therethrough, a plunger centrally located in each knob and extending into said passage in the door, a bolt passing all the way through both casings and the passage in the door and into both knobs said bolt being located at the side of the center and securing both knobs to the door and to each other in fixed position, a push button supported by each knob, and a latch arranged to be operated by each push button through its plunger independently of the other. 95

5. In a push button door knob, the combination with a spring pressed latch, of a pair of stationary knobs on opposite sides of the door in axial alignment with each other, a push button movable in each knob, a plunger positively connected with and movable with each push button, a pair of independent levers pivoted inside the door casing independently of said knobs and having two arms substantially at right angles to each other, one of which each plunger engages, and means connected with said latch, and at a constant distance from the points of pivotal support of the levers irrespective of the thickness of the door, for receiving the end of either lever and withdrawing the latch when either lever is pressed against it by its plunger. 110

In testimony whereof I have hereunto affixed my signature.

MYRON T. HAYER.
